UNITED STATES PATENT OFFICE.

CLARENCE AUGUST SCHAAD, OF WILLIAMS, CALIFORNIA.

SEAL BOX-FASTENER.

No. 849,269.

Specification of Letters Patent.

Patented April 2, 1907.

Application filed August 8, 1906. Serial No. 329,743.

To all whom it may concern:

Be it known that I, CLARENCE AUGUST SCHAAD, a citizen of the United States, and a resident of Williams, in the county of Colusa and State of California, have invented a new and Improved Seal Box-Fastener, of which the following is a full, clear, and exact description.

This invention relates to seal box-fasteners, and is particularly useful in connection with boxes or crates for the shipment of bottles, jugs, and the like, eggs, fruit, &c.

The object of the invention is to provide a seal box-fastener simple, strong, and durable in construction and by means of which a lid may be secured to a box and sealed to prevent tampering with the contents of the box in shipment.

A further object of the invention is to provide a seal-fastener which may be easily manipulated and by means of which the lid may be used to act as a lever to force the contents firmly into the box.

The invention consists in the construction and combination of parts to be more fully described hereinafter and particularly set forth in the claims.

Reference is to be had to the accompanying drawings, forming a part of this specification, in which similar characters of reference indicate corresponding parts in all the figures, in which—

Figure 1 is a perspective view of a box provided with a fastener of my invention. Fig. 2 is a vertical cross-section on the line 2-2 of Fig. 1. Fig. 3 is an end elevation of a portion of a box provided with a fastener of my invention. Fig. 4 is a perspective view of a plate constituting a detail of the invention. Fig. 5 is a perspective view of a bail forming a part of the locking device of my invention, and Fig. 6 is a perspective view of a pin forming a detail of the fastener.

Before proceeding to a more detailed description of the invention it should be understood that while this device can be used for egg-cases, &c., it is particularly applicable to boxes or crates adapted for the transportation of heavy objects, such as large bottles of mineral waters. It is the custom to ship objects of this character from point to point in boxes specially provided for the purpose and to use such boxes repeatedly until they are worn out. It is also customary to nail the

lid upon the box, as there are few satisfactory fasteners which obviate this, and the repeated nailing soon renders the box useless for further shipment. To obviate this, I provide a fastener by means of which a lid may be securely fastened to a box and to which a seal of lead or other similar material may be applied to prevent tampering with the contents of a box *en route*. It is the practice partially to fill the box with a packing material, such as excelsior or shavings, and then to place objects therewithin, after which the lid is fastened to one end of the box. Using the lid as a lever, the objects are forced down into the case until the other end of the lid can be nailed in place. By means of my invention one end of the lid has a movable hinged connection with the box and may be used as a lever for the purpose described.

Referring more particularly to the drawings, 1 represents a box or casing of the usual kind, fashioned of wood or sheet metal and having ends 2, sides 3, and a bottom 4. The ends are provided with vertical lateral cleats 5, nailed or otherwise secured in position. I prefer to have the sides of the box extend beyond the ends flush with the outer faces of the cleats, to the edges of which they may be nailed to provide a strong and durable construction. The ends of the cleats project upwardly beyond the edges of the ends and sides, and between these projecting ends is placed the lid 6. The ends of the cleats prevent the displacement of the lid in a longitudinal direction. At one end of the box is secured a block 7 of substantially rectangular form, as shown most clearly in Fig. 1. The lid is provided with cross-cleats 8 to strengthen the construction.

Secured to the under side of the lid by means of screws or the like and projecting beyond the end thereof are hinge members 9, having separated sleeves 10 at the outer extremity. A bail 11, formed from a strip of metal or the like and having the ends turned at substantially right angles to the plane of the sides of the bail and formed into sleeves 12, is pivotally joined to the hinged members 10 by having the sleeves 12 mounted between pairs of the sleeves 10 and secured in position by means of pins 13 in the usual manner. The bail is adapted to engage with the block 7, as shown most clearly in Fig. 1. The block 7 has a vertical bore near the cen-

ter, within which is located a pin 14, having a flat head 15 and a longitudinal slot 16 in the body thereof. The pin is adapted to slide within the bore of the block 7 and is secured from displacement from said bore by means of a screw or pin 17, passing through the bore and through the slot in the pin.

- It will be understood that the upward or downward sliding movement of the pin is limited by the length of the slot within which the pin 17 is located. The end of the pin 14 when the same is in its lowest position projects from the lower edge of the block and is adapted to pass through an opening 18 in the bail, thus locking the same about the block. The projecting end of the pin 14 is provided with an opening 19, through which may be passed a wire 20, having the ends thereof secured together by a leaden seal 21 in the usual manner.

Secured to the under side of the lid and projecting beyond the opposite edge thereof are plates 22, having openings 23, through which screws or bolts may be inserted to secure the plates to the lid. The ends of the plates projecting beyond the end of the lid have slots 24, adapted to engage with the laterally-disposed ends 26 of plates 25, which are fastened to the end of the box by means of bolts or screws. The ends 26 are laterally and outwardly disposed and form, together with the plates 22, a hinged connection between the lid and the box, and it is impossible to separate the plates 22 and 25 without breaking the closure when the outward end of the lid is secured in place by means of the bail.

When the pin 14 is freed from the seal and pulled outward out of engagement with the opening 18 in the bail, the latter may be rocked upwardly from engagement with the block 7, and is thus adapted to serve as a handle to raise the lid on the hinges at the opposite end formed by the plates 22 and 25.

- It will be understood that the lid may be used as a lever to force the contents of the box inward if the end carrying the bail is pressed downward while the plates 22 and 25 are in engagement. The lid may be completely separated from the box by raising the lid and pushing the same backward, so that the laterally-disposed ends 26 of the plate 25 may slip out of the slots 24 in the plates 22, which have assumed a substantially vertical position. The lid is held upon the box secure from longitudinal displacement by the projecting ends of the cleats 5. The lid is also secured from lateral displacement by the engagement of the bail with the block and by the connection at the opposite end of the lid. More firmly to secure the lid upon the box the arrangement is such that the projecting hinge members at both ends of the lid are located between the end cleats 5 and adjacent to these, so that in case of lateral pressure

the projecting members will abut against the cleats, which resist the displacement.

Having thus described my invention, I claim as new and desire to secure by Letters Patent—

1. The combination with a box having a block at an end thereof and a lid hinged at the other end of said box, of a bail having a hinged connection with said lid and adapted to engage with said block, said bail having an aperture, and a pin slidably mounted within said block and adapted to engage with said aperture of said bail. 70

2. The combination with a box having a block at an end thereof and a lid hinged at the other end of said box, of a bail having a hinged connection with said lid and adapted to engage with said block, said bail having an aperture, a pin slidably mounted within said block and having a slot, a rigid pin in said block transverse of said first pin and passing through said slot, said first pin being adapted to engage with said aperture of said bail and projecting therethrough, and means for attaching a seal at the end of said pin. 85

3. The combination with a box having a block and cleats at an end thereof and a lid hinged at the other end of said box, of a bail having a hinged connection with said lid and adapted to engage with said block between said cleats, said bail having an aperture, and a pin slidably mounted within said block and adapted to engage with said aperture of said bail. 90

4. The combination with a box having a block at an end thereof, laterally-disposed projections at an opposite end thereof, and a lid having openings adapted to engage with said projections, of a bail having a hinged connection with said lid and adapted to engage with said block, said bail having an opening, said box having cleats at the ends thereof adjacent to said block and said projections, said block having a pin slidably mounted therewithin adapted to be projected into said opening of said bail to secure the same in position in said opening of said block. 100

5. In a box-closure, a block secured to an end of a box, a bail hinged to a lid and adapted to engage with said block in a depressed position and constitute a handle to raise said lid when said bail is in a raised position, the bail having an aperture, said block having a pin slidably mounted therewithin and adapted to project from the block through said aperture, and means for attaching a seal to the projecting end of the pin. 115

6. In a box-closure, a plate having a laterally-disposed end mounted at an end of the box, a second plate having an opening mounted at the end of a lid, said laterally-disposed end being adapted to engage within said opening, a block mounted upon said box, a bail mounted upon said lid and having a 125

130

hinged connection therewith, said bail being
adapted to engage with said block in a de-
pressed position and having an aperture, a
pin slidably mounted within said block and
adapted to engage within said aperture, and
a rigid pin in said block adapted to limit the
projection of said first pin from said block.

In testimony whereof I have signed my
name to this specification in the presence of
two subscribing witnesses.

CLARENCE AUGUST SCHAAD.
